United States Patent Office

Des. 185,466
Patented June 9, 1959

185,466

SHOE BRUSH

Leidy G. Scholl, Lansdale, Pa.

Application April 30, 1957, Serial No. 45,949

Term of patent 14 years

(Cl. D9—2)

Fig. 1

Fig. 2

The dominant features of the design reside in the portions shown in full lines.

I claim:

The ornamental design for a shoe brush, as shown and described.
